UNITED STATES PATENT OFFICE

AXEL JOHNSON, OF STAVELY, ALBERTA, CANADA

PORTABLE HEATER FOR DRYING GRAIN

Application filed October 26, 1927. Serial No. 228,936.

This invention particularly relates to improvements in portable heaters for drying grain and the like and the object of the invention is to provide an apparatus of this description that will effectively dry damp and tough grain by means of air at a predetermined temperature.

A further object of the invention is to provide a heater of this character which may be readily combined with other types of apparatus for handling grain.

With the above and other objects in view, the invention resides essentially in a portable heating chamber and blower, more fully described in the present specification and illustrated in the accompanying drawings.

Referring now to the drawings in which like characters of reference indicate corresponding parts in each figure:

29 Figure 1 is a side elevation partly in section of my complete grain drying plant.

Figure 2 is a fragmentary sectional view of a granary for storing grain, the supporting means for the hose and nozzle being shown in elevation.

Figure 3 is a perspective view of the perforated grain drying pipes.

Figure 4 is a front elevation of the air heater.

30 Figure 5 is a longitudinal section of the heater and spark arrester.

Figure 6 is a side elevation of the nozzle.

Figure 7 is an enlarged section on line 7—7 of Figure 6.

33 Figure 8 is a fragmentary plan of the engine bed or channel iron showing the slots.

Figure 9 is a longitudinal section through the flanged ferrule.

Figure 10 is an enlarged end view of the blower.

Figure 11 is a section on line 11—11 of Fig. 10.

Figure 12 is a plan view partly in section of the two-way outlet and valve mechanism.

45 Figure 13 is a section on the line 13—13 of Fig. 10.

Figure 14 is a front elevation of the supporting bracket for the hose.

Referring more particularly to the drawings, 50 10 designates a wheel truck on which

is mounted at one end a heating chamber or furnace 11, provided with a plurality of longitudinally extending air tubes 12 communicating with chambers 13 and 14 at each end which in turn communicate with the discharge pipe 15 and an intake pipe 16 respectively. For the discharge of the products of combustion a flue pipe 17 is provided extending outwardly and downwardly into a humidifier or container 18, in which is water, whereby 60 sparks and the like coming through the flue 17 are eliminated. The container 18 is provided with a discharge pipe 19.

It will thus be seen that on the furnace 11 being fired the air in the tubes 12 will be at 65 once heated, providing a source of heat supply (see Fig. 5). Connected to the intake pipe 16 in any suitable manner (see Fig. 1) by means of a flexible section 20 is a blower 21 (see Figs. 10 and 11) provided with a 70 two-way air outlet 22 rounded at the end for hose connection (see Fig. 12), one arm 23 of which is connected to the flexible section 20 and thence to the air heater 11 to grain drier 24, and the other arm 25 may be connected to a suitable grain conveyor member 26 through the hose 27, the blower thereby being adapted to a dual function, as herein-after more fully referred to.

Between the chamber 13 within the furnace 11 and flue pipe 17 a conduit 28 is positioned downwardly turned at one end within the flue 17 and conforming to the shape thereof. A portion of the air entering the chamber 13 from the blower will pass through the 80 conduit 28, the amount being regulated by the valve 29 intermediately positioned on the conduit 28 so that the draft in the flue 17 may be considerably intensified which will provide for the ready elimination of the products of combustion from the furnace chamber and will provide for the forcing of these products into the water contained in the container 18 for spark arresting purposes. The blower 21 associated with the furnace structure is provided with the usual drive shaft 30 journaled in suitable pillow blocks 31 so that the shaft protrudes from the blower casing at one end and is provided with a pulley 32. By means of a belt 33 the pulley 32 is connected with 100

a motor or prime mover 34 of any suitable character so that air is forced from the blower through the adjacent connections to the furnace 11.

The blower 21 further comprises a plurality of fans or wings 35 (see Figs. 10 and 11) passing between the stationary partitions 36. The fans or wings are composed of metal and being bent in shape to make two wings are then riveted to the circular revolving partitions 37. The stationary partitions 36 are provided with a large air passage 38 in the centre and are then notched into staves 39 on the outside circumference and holding the return guide vanes 40 adapted to lead air back through centre and more directly, thus counteracting the rotary motion set up which would tend to greatly reduce the efficiency of the blower.

A pressure gauge 41 is provided on the two-way outlet 22 to indicate the amount of resistance in operation, and thereby the amount penetrating the grain, as hereinafter more fully referred to. This will materially assist in selecting size and power of plants for individual undertakings. Also on the two-way outlet are the hose connections the hose 20 leading to the air heater 11, and the hose 27 leading to grain conveyor 48. Both may be used at the same time or independently by the use of the valve 48^a, the valve being retained in any position by the hand screw 48^b.

From the foregoing it will be seen that on operation of the blower 21 and the generation of heat in the furnace 11 the air passing from the blower through the conduit 16 to chamber 13 and thence through tubes 12 to chamber 14 will be heated during this passage and will subsequently pass through conduit 15 in heated condition under pressure to be delivered to a suitable distributor, as shown and herein referred to, while a portion of the air, as previously referred to, will pass through the conduit 28 providing a more intense draft in the flue 17 through which the products of combustion pass which are subsequently delivered through the medium of the water in the container 18 to the stack discharge pipe 19.

This type of heating apparatus, as referred to, may be associated with suitable distributing and other mechanisms such as illustrated. The distributing member in connection with the discharge pipe 15 includes a main vertical pipe 42 (see Figure 3) communicating with horizontally extending branch pipes 43 and 44 in turn provided at spaced intervals with a plurality of distributing, suitably bent branch pipes 25 connected to perforated lengths of pipes 46 adapted to be inserted into the grain at any angle. In this way the predetermined air from the chamber 11 is injected into the grain as illustrated in Fig. 1 in the granary or the like 47.

For removing grain from a granary, the air conveyor hose 27 is connected to a grain conveyor 48, this being provided with a suction head 49, suction being induced or generated by the blast or air current through the nozzle 50 from air hose 27, as indicated by dotted lines in Fig. 2. The grain during the operation will follow the outside curve so that the air nozzle will not obstruct its course. A grain delivery hose 51 may also be provided for delivering grain into wagons or other special places. For supporting the air conveyor hose 27 and the grain conveyor 48 I provide, as illustrated in Fig. 14, a support consisting of rods 52 and 53 secured to brackets 54 and provided with a clamping member 55 at the top to engage with the hose. A chain 56 is also provided at the top to retain the hose supporting member at any required angle.

As illustrated in Figs. 2, 6 and 7, handle means 57 are provided for conveying the nozzle 50 from place to place. I also provide tightening means as illustrated in Fig. 8 in the form of slots 58 in the frame 10, so that the blower 21 may be moved to take up the slack of the belt 33, while in Figs. 1 and 9 is disclosed a filler or flanged ferrule 59 designed to fit into the wall of the granary, so that the pipes 46 may be conveniently inserted through the wall into the grain. These ferrules may be plugged to prevent spilling of grain and left in the walls. These are important details in the construction, materially assisting in facilitating the erection of the apparatus and the satisfactory working thereof when erected.

From the foregoing the operation of my device will be apparent. When it is desired to simply dry grain in a granary, the heat chamber or furnace 11 is started and with the blower 21 delivering at a predetermined temperature under pressure a current or blast of hot air through the distributing system and the perforated pipes 46 into the grain. When it is desired, on the other hand, to remove grain from one place to another, or from a granary into wagons, the blower 21 is operated and a suction placed through the air conveyor 27 provided within the granary, causing the grain to be discharged through the hose 46 to any desired point.

As many changes could be made in the above construction, and many apparently widely different embodiments of my invention, within the scope of the claim, constructed without departing from the spirit or scope thereof, it is intended that all matter contained in the present specification and accompanying drawings shall be interpreted in an illustrative and not in a limiting sense.

What I claim as my invention is:

A portable heater for drying grain comprising a combustion chamber, a grate in said chamber, air compartments at each end of the

chamber, air conducting tubes between the air compartments, an air inlet in connection with one compartment, and an air outlet in connection with the other compartment, a discharge conduit in connection with the chamber for the products of combustion, a draught inducing conduit connected with one of the air compartments and opening into the discharge conduit, valve means for regulating the draught inducing conduit, a blower connected to the air inlet and spark arresting means in connection with the discharge conduit.

In witness whereof I have hereunto set
13 my hand.

AXEL JOHNSON.
